ENGINE

Robert T. Larsen, Menomonee Falls, Wis., assignor to Outboard Marine Corporation, Waukegan, Ill., a corporation of Delaware

Filed Dec. 9, 1963, Ser. No. 328,813
9 Claims. (Cl. 123—41.47)

The invention relates generally to marine propulsion devices, such as outboard motors.

The invention provides a sound isolating barrier between the power head and the lower unit or strut. The barrier comprises a pair of mounting plates adapted to be respectively secured to the head and to the lower unit, and a sheet of resilient material, such as rubber, which is bonded to and between said plates throughout substantially the entire area thereof. Connection of the power head and lower unit to the plates therefore results in a unitary assembly including a layer or barrier of resilient material which excludes sound and also serves to dampen vibration.

In the preferred construction, the barrier includes means affording communication between an engine exhaust gas discharge port and an exhaust gas passage in the lower unit, together with means affording communication between a water pump in the lower unit and an engine cooling jacket. Preferably, passage of coolant water through the barrier is arranged to effect cooling of the barrier, and particularly, cooling of the resilient material in the area surrounding the flow of exhaust gas. The barrier also includes an aperture or bore for the passage of the engine crankshaft or the lower unit driveshaft to facilitate their driving connection.

Other objects and advantages of the invention will become known by reference to the following description and accompanying drawings in which

FIGURE 1 is a partially broken away and sectioned view of an outboard motor embodying various of the features of the invention;

FIGURE 2 is an enlarged view, partially in section, of a portion of the outboard motor shown in FIGURE 1;

FIGURE 3 is a sectional view taken along line 3—3 of FIGURE 2;

FIGURE 4 is an enlarged fragmentary sectional view taken along line 4—4 of FIGURE 3;

FIGURE 5 is a view similar to FIGURE 2 showing a modified construction;

FIGURE 6 is a sectional view taken along line 6—6 of FIGURE 5;

FIGURE 7 is a view similar to FIGURE 5 showing another modified construction;

FIGURE 8 is a fragmentary sectional view taken along line 8—8 of FIGURE 7;

FIGURE 9 is a fragmentary sectional view taken along line 9—9 of FIGURE 7;

FIGURE 10 is a fragmentary sectional view taken along line 10—10 of FIGURE 7;

FIGURE 11 is a view similar to FIGURES 3 and 5 showing another modified construction; and

FIGURE 12 is a sectional view taken along line 12—12 of FIGURE 11.

Shown in FIGURE 1 is an outboard motor 11 of generally conventional construction except that the power head 13 is connected to the lower unit 15 to form a unitary propulsion unit by a sound isolating barrier 17 in-

2

terposed between the power head and the lower unit. As is common practice, the power head 13 includes an internal combustion engine 19 having a crankshaft 21, a coolant jacket 23, and an exhaust gas discharge port 25.

5 The lower unit 15 is constructed with an exhaust gas discharge passage or conduit 27, and mounts a driveshaft 29 which is drivingly connected to a propeller 31 and which is also drivingly connected to the engine crankshaft 21. In addition, the lower unit 15 supports a water pump 33 which is driven by the driveshaft 29 and which 10 communicates with the engine water jacket 23 by means not shown in FIGURES 1 through 4.

The assemblage of the lower unit 15 and the power head 13 is supported by vibration and sound damping 15 mountings in a shroud 35 including an engine cover 37, as disclosed in the Watkins Patent No. 3,002,489. The shroud 35 is pivotally mounted on a swivel bracket 39 which, in turn, is supported by a transom bracket 41 adapted to be mounted on the transom 43 of a boat. 20 The power head and lower unit therefore vibrate independently of and within the shroud 35.

If desired, the motor cover can be directly connected with the assemblage of the power head and lower unit, which assemblage can be supported from a transom 25 bracket by vibration and sound damping mountings as disclosed in the Irgens Patent No. 2,740,368. However, in order to take advantage of the present invention, it is 30 desirable to connect the engine cover to the lower unit independently of any rigid connection with the power head.

The barrier 17 serves to at least partially exclude the 35 transmission of sound from the power head 13 to the lower unit 15, to assist in damping vibrations set up in the power head 13, and to connect the power head 13 and the lower unit 15. The barrier 17 comprises a sheet 45 of resilient material which is interposed between and bonded to a pair of mounting plates 47 and 49. The mounting plate 47 is bolted or otherwise secured to the power head 13 while the other mounting plate 49 is bolted or otherwise secured to the lower unit 15. The sheet 45 extends generally continuously between the mounting plates 47 and 49 and can be fabricated of resilient material such as rubber.

The barrier 17 also includes provision for affording 45 communication between the exhaust gas discharge port 25 of the engine and the exhaust gas passage 27 in the lower unit 15. In the illustrated construction, such means takes the form of an aperture 51 extending through the barrier, and an exhaust port sleeve 53 which extends from the engine 19 through the aperture 51 and to the exhaust gas passage 27 in the lower unit 15. It is to be noted that the portion of the aperture 51 extending through the lower mounting plate 49 is free of 50 direct contact with the sleeve 53 and with the engine 19 as a whole.

55 Preferably, the portion of the barrier surrounding the exhaust gas aperture 51 is cooled to prevent deterioration of the resilient material and to otherwise reduce the temperature in this area. In the embodiment shown in FIGURES 1, 2, and 3, the sheet 45 and the adjacent faces of the mounting plates 47 and 49 are formed to provide a conduit means including a circular passage 55 generally surrounding the exhaust aperture 51. At its ends, the passage 55 communicates with respective bores 57 and 59 extending through the lower mounting plate 49. The

bore 57 communicates through conduit 61 with the discharge port of the water pump 33 while the bore 59 communicates through a conduit 63 which empties into the exhaust gas passage 27. Thus, during engine operation, the portion of the barrier 17 around the exhaust gas aperture 51 is continuously cooled.

In addition to the provision for exhaust gas flow, the barrier 17 also includes another aperture 65 for passage of the crankshaft 21 or of the driveshaft 29 to permit their interconnection in driving engagement. In the construction shown in the drawings, the driveshaft 29 extends through the aperture 65 without contacting the barrier 17 and is splined to the crankshaft 21 at a point above the barrier.

When the power head is adapted to be water cooled, provision is also made for the passage of coolant through the barrier. In the embodiment shown in FIGURE 2, separate bores (not shown) are provided for passing supply and discharge coolant water through the barrier. Such coolant flow is preferably employed to cool the portion of the barrier 17 surrounding the exhaust gas aperture 51. Thus, in the embodiment shown in FIGURE 5, the conduit 161 carrying the discharge from the water pump 133 communicates with a bore 157 extending through the lower mounting plate 149. In turn, the bore 157 communicates with one end of a circularly extending recessed passage 155 similar to the passage 55. At its other end, the passage 155 is connected with a bore 159 which extends through the upper mounting plate 147 and which is in communication with the cooling jacket 123 of the engine 119.

Discharge flow from the engine cooling jacket 123 passes through a bore 169 extending through the barrier 117 and communicating with a conduit 163 which, in the case of a bypass cooling system, discharges into the exhaust gas passage 127 or, in the case of a recirculating system, discharges into a supply port in the water pump 133. In some recirculating systems, the thermostat controlling coolant recirculation is located in the power head. Under these circumstances, another bore (not shown) can be provided through the barrier.

In the embodiment shown in FIGURE 7, a pair of circularly extending passages 255a and 255b, located respectively in the mounting plates 247 and 249, are connected in series to cool the barrier 217 in the area of the exhaust gas aperture 251. Specifically, the conduit 261 extending from the water pump discharge communicates with a bore 257 extending through the mounting plate 249, which bore is connected to one end of the passage 255b surrounding the exhaust gas aperture 251. At its other end, the circularly extending passage 255b communicates with a bore 271 which passes through the resilient sheet 245 and which communicates with one end of the other circularly extending passage 255a in the upper mounting plate 247. At its other end, the passage 255a communicates with a bore 259 which, in turn, communicates with the cooling jacket 223 of the engine. One or more additional bores 269 through the barrier 217 can be provided for discharge or recirculating flow as desired.

In the embodiment shown in FIGURE 11, both the coolant flow to the water jacket 323 and the discharge flow from the water jacket are employed to cool the barrier 317 in the area of the exhaust gas discharge flow. Specifically, the conduit 361 extending from the water pump discharge communicates, through a bore 357a in the mounting plate 349, with one end of an arcuately shaped passage 355a which extends partially around the exhaust gas aperture 351. At its other end, the passage 355a communicates with a bore 357b through the upper mounting plate 347. In turn, the bore 357b communicates with the engine water jacket 323. Discharge from the engine water jacket 323 is carried by another bore 359b which extends through the upper mounting plate

347 and communicates with one end of an arcuate passage 355b in the barrier, which passage also extends partially around the exhaust gas aperture. At its other end, the passage 355b communicates with a bore 359a which extends through the lower mounting plate 349 and which is in communication with a conduit 363 connected with a discharge outlet or with a supply port on the water pump, as desired.

As seen in FIGURE 12, the arcuate passages 355a and 355b substantially completely surround the exhaust gas aperture 351. As in the other embodiments, an additional bore (not shown) through the barrier 317 can be provided in the case of a recirculating system utilizing three flow connections between the power head 313 and the lower unit 315.

Various of the features of the invention are set forth in the following claims.

What is claimed is:

1. An outboard motor including a power head, a lower unit, and means connecting said power head and said lower unit including a pair of mounting plates and a resilient sheet bonded to and between said plates, one of said plates being connected to said power head and the other of said plates being connected to said lower unit.

2. An outboard motor including a power head including an internal combustion engine having an exhaust gas discharge port, and a coolant water jacket, a lower unit including a water pump, and an exhaust gas passage, and barrier means connecting said power head and said lower unit and including a pair of mounting plates and a resilient sheet bonded to and between said plates, one of said plates being connected to said power head and the other of said plates being connected to said lower unit, said barrier means also including means affording communication through said barrier means between said exhaust gas passage and said exhaust gas discharge port, and means affording communication through said barrier means between said water pump and said water coolant jacket.

3. An outboard motor in accordance with claim 2 wherein said means affording communication between said water pump and said coolant jacket includes conduit means extending through said barrier means in the area adjacent to said means affording communication between said exhaust gas passage and said exhaust gas discharge port.

4. An outboard motor in accordance with claim 3 wherein said conduit means extends substantially completely around said means affording communication between said exhaust gas passage and said exhaust gas discharge port.

5. An outboard motor in accordance with claim 4 wherein said conduit means includes a passage located at least partially in said resilient sheet and at least partially encircling said means affording communication between said exhaust gas passage and said exhaust gas discharge port.

6. An outboard motor in accordance with claim 4 wherein said conduit means includes passages located entirely in said mounting plates, and at least partially encircling said means affording communication between said exhaust gas passage and said exhaust gas discharge port.

7. An outboard motor in accordance with claim 3 wherein said conduit means includes a first passage at least partially encircling said means affording communication between said exhaust gas passage and said exhaust gas discharge port for supplying coolant to said engine jacket, and a second passage at least partially encircling said means affording communication between said exhaust gas passage and said exhaust gas discharge port for discharging coolant from said engine jacket.

8. An outboard motor in accordance with claim 3 wherein said conduit means includes, in series, two passages each substantially encircling said means affording

communciation between said exhaust gas passage and said exhaust gas discharge port.

9. An outboard motor in accordance with claim 1 wherein said means affording communication between said exhaust gas passage and said exhaust gas discharge port comprises an aperture in said barrier means and said engine includes an exhaust gas discharge tube extending through said aperture free of contact with said other plate.
